OTHER PUBLICATIONS

Co-pending U.S. Appl. No. 29/461,249, filed Jul. 19, 2013.
(Continued)*Primary Examiner* — Robert M Spear
Assistant Examiner — Kendra L Hamilton(57) **CLAIM**

The ornamental design for a container lid, as shown and described.

DESCRIPTION

FIG. 1 is a top perspective view of a container lid showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view thereof.

The broken lines in the Figures show portions of the container lid which form no part of the claimed design. The dot-dash lines in the Figures show unclaimed boundaries which form no part of the claimed design.
